DESIGN FOR A TEAKETTLE

Albert D. Mortrude, Detroit, Mich., assignor to
Kromex Corporation, Cleveland, Ohio, a cor-
poration of Ohio

Application June 12, 1947, Serial No. 139,612

Term of patent 14 years

(Cl. D44—25)

To all whom it may concern:

Be it known that I, Albert D. Mortrude, a citizen of the United States, residing at Detroit, county of Wayne, and State of Michigan, have invented a new, original, and ornamental Design for Teakettle, of which the following is a specification, reference being had to the accompanying drawing, forming a part thereof.

Fig. 1 is a side elevational view of a teakettle showing my new design;

Fig. 2 is a top plan view;

Fig. 3 is a front elevational view, and

Fig. 4 is a rear elevational view thereof.

I claim:

The ornamental design for a teakettle, substantially as shown.

ALBERT D. MORTRUDE.
